INTERNAL COMBUSTION ENGINE
APPARATUS

Heinrich Wälti, Winterthur, Switzerland, assignor to Sulzer Freres, Societe Anonyme, Winterthur, Switzerland

Application September 22, 1936, Serial No. 101,894. In Switzerland October 1, 1935

3 Claims. (Cl. 123—57)

This invention relates to internal combustion engines and particularly to auxiliary apparatus for the production of scavenging-air therefor. The auxiliary apparatus of the invention comprises one or more power pistons each of which is connected in tandem to and drives an air compressor piston for supplying scavenging-air to the engines. The power and compressor pistons are mounted on the same piston rod, in spaced relation, with the compressor piston between the power piston and a crankshaft which is common to both. The power and compressor pistons are reciprocable in their respective cylinders which are separated from each other a suitable distance. For this purpose a spacing member is used which also serves to permit inspection of the power piston during substantially its entire stroke, and to prevent air pollution, as will later be described.

It is an object of the invention to provide a combination of the foregoing described scavenging-air apparatus with an internal combustion engine, particularly of the two-cycle type such as are used for power plants. The invention also contemplates the provision of means for circulating a cooling medium through the piston rod and in contact with the power piston.

The invention will be better understood from a consideration of the following description taken in conjunction with the accompanying drawing, in which

Fig. 1 is a schematic illustration of apparatus in accordance with the invention;

Fig. 2 is an elevation, with certain parts shown in section, of the scavenging-air apparatus of the invention taken along the line 2—2 of Fig. 3; and

Fig. 3 is an elevation, with certain parts shown in section, taken along the line 3—3 of Fig. 2.

Fig. 1 illustrates a combination of apparatus in accordance with the invention comprising two ten-cylinder two-cycle internal combustion engines 1, having scavenging-air manifolds 2 and 3, an exhaust conduit 4, and auxiliary apparatus 5 for the production of scavenging-air for the said engines which includes a scavenging-air receiver 6 connected to the manifolds 2 and 3, and an exhaust conduit 7 which is connected to the exhaust conduit 4 of the engines.

The auxiliary machine 5, for compressing scavenging-air (illustrated in detail in Figs. 2 and 3) consists of two cylinder-units each of which is similar and the following description in the singular is understood to refer to each unit. Each unit has a power piston 8 reciprocable

within a combustion or power cylinder 9. The power piston is mounted on a piston rod 10 on which a compressor piston 11 is mounted in tandem therewith and reciprocable in a compression cylinder 12. The power and compression cylinders are preferably arranged in upright positions and are spaced apart by means of the spacing member or lantern 13, having an opening 14 therein which not only permits inspection of the power piston over the greater part of its length but also prevents pollution of the scavenging and charging air by exhaust gases or partially carbonized oil from the combustion cylinder 9. The common piston rod 10 engages the crosshead 15 of the connecting rod 16 which is mounted upon the crankshaft 17.

A tubular slide-valve 18, mounted adjacent one side of the compression cylinder 12, is driven from the crankshaft 17 by the eccentric connecting rod 19, the double lever 20 and guide rod 21. The piston compressor 11 is double acting and provided with valve-controlled openings 22 and 23, each of which serves as both an inlet and an outlet opening for the compression cylinder. An inlet conduit 24 supplies air from the outside to the circumferential opening or passage 25 around the central portion of the slide valve 18. The opening 22 connects directly with the receiver 6 and the opening 23 connects through the central opening 23a in the valve 18, with the receiver 6.

The power piston 8 is constructed and arranged to receive its scavenging-air from the receiver 6 by means of a conduit 26 which is in communication with the ducts 27 which are controlled by the check-valves 28. The ports 27 lead directly into the cylinder 9 through suitable scavenging and charging ports. The head 31 of the power cylinder is provided with a fuel valve 32 of known construction which is supplied with fuel oil under pressure from any suitable source (not shown).

The bottom 33 of the lantern 13 is sloped to one side and at the low point is connected with a pipe 34 into which oil, wiped off the piston rod 10, may be drained.

The under portion of each power piston is cooled by means of a circulated fluid cooling-medium. For this purpose, the piston rod 10 has a central bore 35 and a concentric inner tube 36. The tube 36 connects with an inlet opening 37 in the crosshead 15 which connects with a tubular telescopic member 38 connected to a conduit 39 leading to a suitable source of cooling medium such as oil under pressure (not shown). The conduit 35 connects with the outlet opening

40 connected to a second tubular telescopic member 41 which connects to a conduit 42 leading to the source of cooling medium or to waste.

The power capacity of each power cylinder is 5 not appreciably more than necessary to operate the compressor piston. As the combustion power piston cylinder 8 is single-acting, but works in two-cycle, and the auxiliary machine 5 has two cylinder units, the cranks of which are displaced 10 by 180° with respect to each other, the arrangement is balanced with respect to the distribution of output. In the case of a single cylinder unit a flywheel would have to be provided in order to be able to deliver the compression work in the 15 double-acting compressor and in the combustion power cylinder at the compression stroke of the combustion power piston. Multi-cylinder scavenging-air producers have the advantage of a good balancing of masses as has already become 20 known in connection with combustion engines.

The apparatus functions as follows: Air is passed from the receiver 6 through the conduit 26, the check-valves 28, the ducts 27 and through charging and scavenging ports (not shown) into 25 the cylinder 9. As the power piston moves upwardly, the air is compressed whereupon oil is injected into the cylinder 9 by means of the valve 32. The oil is ignited and the piston begins to move downwardly moving the compressor piston 30 in the same direction. As the compressor piston begins to move downwardly, the slide valve 18 is in the position shown in Fig. 2, and the slide valve moves upwardly clearing the opening 22 so that air is sucked into the compression cylinder 35 through conduit 24 and passage 25. At the same time valve 18 clears opening 22 permitting the air to be forced out of the compression cylinder through the opening 23a and into the receiver 6. Valve 18 continues to move upwardly and into 40 the cylindrical bore 22a thereby closing the passageway between opening 22 and the receiver 6. As the piston 11 reaches the lower end of its stroke and starts upwardly, the valve 18 clears the opening 23, permitting air to be sucked into the 45 cylinder 12, and continues to move downwardly into the bore 24a closing the passageway between opening 23 and the receiver 6. Meanwhile the power piston has cleared the ports 30 permitting the burned gases to exhaust into the conduit 7. At this point scavenging-air is again admitted 50 to the power cylinder.

As the assembly of pistons again moves upwardly, the valve 18 moves upwardly clearing the opening 22 and permitting the compressor piston 55 11 to force the scavenging-air into the receiver 6. The scavenging-air flows from the receiver 6 to the main engines 1 where it is used in the usual way.

In cooling the power pistons, the fluid cooling 60 medium is pumped into the opening 39, through

the telescopic member 38, the passageway 37 in the crosshead 15 and then upwardly through the tube 36 and in contact with the piston. The fluid then enters the bore 35 where it connects with the piston and flows through the outlet opening 5 40, into the telescopic member 41, and into the conduit 42 from which it is either discharged to waste or returned to the source of cooling medium.

In the foregoing description of operation, reference has been made to only one unit, it being understood that each unit in the system would operate similarly.

The auxiliary machine for producing the scavenging-air can also be formed as a floating-piston 15 engine, since the power and compressor pistons work as floating pistons without a crank drive.

I claim:

1. In combination, an internal combustion-engine plant including at least one principal combustion engine of the type requiring scavenging or charging air, and a separate auxiliary air compressor unit supplying said air for said principal combustion engine, said auxiliary unit comprising at least one engine-driven compressor including 25 an engine cylinder, an engine piston, a piston rod, a connecting rod, a crank, an air pump cylinder arranged between said engine cylinder and said crank, and an air pump piston arranged in said pump cylinder on said piston rod between said 30 engine piston and said connecting rod, a spider securing said engine cylinder to said pump cylinder in such manner that said engine piston is exposed between said cylinders, whereby to allow inspection of said engine piston during operation 35 and to prevent pollution of said air, and an air conduit directly connecting said principal combustion engine and said air compressor unit to convey said scavenging or charging air.

2. An internal combustion engine plant according to claim 1 wherein said principal engine comprises a plurality of rows of power cylinders the scavenging air for which is supplied by an auxiliary air-compressor unit comprising only a few cylinders compared with the number of cylinders 45 in said principal engine.

3. In combination with an internal combustion engine, auxiliary apparatus for the production of scavenging-air therefor, which comprises a power piston, a compressor piston, a crank, a piston rod 50 on which both pistons are mounted in tandem with said compressor piston between said power piston and said crank, cylinders for said pistons, a spider for supporting the cylinders in spaced relation whereby to allow inspection of said engine piston during operation and to prevent pollution of said air, and an air conduit directly connecting said auxiliary apparatus and said combustion engine to convey said scavenging air.

HEINRICH WÄLTI. 60
